UNITED STATES PATENT OFFICE.

WILLIAM H. GATES, OF NEW HAVEN, CONNECTICUT.

DIE-HEAD ATTACHMENT.

1,209,140.

Specification of Letters Patent. Patented Dec. 19, 1916.

Application filed September 10, 1915. Serial No. 49,897.

To all whom it may concern:

Be it known that I, WILLIAM H. GATES, citizen of the United States, residing at New Haven, in the county of New Haven and State of Connecticut, have invented certain new and useful Improvements in Die-Head Attachments; and I do hereby declare the following to be a full, clear, and exact description of the invention, such as will enable others skilled in the art to which it appertains to make and use the same.

My invention relates to die heads and is an improvement on the construction shown and described in the patent granted to me on August 3, 1915, No. 1,148,510.

The present improvement consists in the application of a stop for automatically opening the threading dies, and mechanism for effecting a roughing and finishing cut, and it is particularly adapted to die heads used on hand operated machines.

Referring to the accompanying drawings in which—

Figure 1 represents a broken view partly in section of the die head; Fig. 2 is an upper plan view of the die head and broken view of the shank of the holder; Fig. 3 is a front elevation of the die head; Fig. 4 is a broken side elevation partly in section of the die head; Fig. 5 is a broken sectional view of the sliding shell on line 5-5 of Fig. 4; Fig. 6 is a detail side elevation of the cam disk connected with the thread cutting mechanism; Fig. 7 is a detail view of the trip lever; Fig. 8 is a detail bottom plan view of the segment connected with the thread cutting mechanism; Fig. 9 is a detail view of the indicator dial; Fig. 10 is a detail bottom plan view of the cam disk; and Fig. 11 is a detail view of the locking bolt for maintaining the sliding shell in close relation with the die carrying head.

The head 1 is provided in its forward end with the slots 2 to receive the threading dies 3. Said head is mounted in the mouth of the holder 4 and has a longitudinal movement therein. The shank 5 of said holder is adapted to enter any movable member—not shown—like, for instance, a turret head 50 mounted on a longitudinally movable slide.

The shell 6 embraces both the holder 4 and the die head 1 and has a longitudinal movement on each. 7 are studs anchored in the sliding shell 6 and are secured thereto by pins, two of which, 8, are shown in Fig. 1.

The forward ends of these studs are provided—as in my former patent,—before mentioned—with cams 9, Fig. 1, to operate in the cam grooves 10, Fig. 3, to actuate the threading dies to open and close. These 60 studs have a free longitudinal movement in the holes 11 of the head.

When the threading dies are in position for cutting threads, the head 1 and sliding shell 6 are locked together as shown in Figs. 1, 2 and 4, as follows: 12, Fig. 6, is a disk rotatably mounted in the sliding shell whose bottom, Fig. 10, is provided with the cam recess 13 to admit the upper end 14 of the locking bolt 15, Fig. 11, and is temporarily held therein by the spring 16, Fig. 4. The indicator dial plate 17, Fig. 9, rests against the shoulder 18, Fig. 6, and also in the recess 19, Fig. 4. 20—see also Fig. 8—is a segment provided with the hole 21 adapted to embrace the stud 22 of the cam disk 12 and overlie the same. The indicator dial plate is secured to the disk by the screw 17, Fig. 9, and the segment is secured to the disk by the nut 23, Figs. 2, 4 and 5.

24 is a trip rod passing freely through the upper end of the trip lever 25, pivotally supported on the pin 26, Fig. 4, carried by the head 1. The threaded end 27 is adjustably supported in the stud 28 secured to the head 4 of the holder. The jam nuts 29 locate the head 30 of the trip rod with respect to the trip lever to regulate the travel of the head. The lower end or arm 31 of the trip lever is located in the notch 32 of the locking bolt 15 when the die carrying head 1 and sliding shell 6 are locked together as shown in Fig. 4.

When the holder has been moved forward by a turret or other like means and engaged the threading dies with the work—not shown—the head 1 will be drawn forward in the mouth of the holder a distance representing the length of the thread to be cut, when the trip lever will contact with the head 30 of the trip rod and cause said lever to tilt on its pivotal support and depress the locking bolt 15 a distance sufficient to release its upper end 14 with its engagement with the disk cam and permit the sliding shell to be disengaged from the head 1 and carried back by means of the springs 33, Figs. 3 and 4, which rearward movement is limited by means of the inner end of the spring actuated pin 34 traveling in the slot 35, Fig. 110

4, located in the shell. The head 1 is also automatically returned by the stored up tension in the spring 36. This spring is located between the shoulder 37 of the holder 5 shank 5 and the nut 38 mounted on the outer threaded end of the head extension rod 39, so that, when the head is moved forward, the spring 36 will be compressed and sufficient force stored up therein to return the head 10 as before mentioned. When the head and shell have thus been retreated, the latter will lie in close proximity to the cam 40 which is manually actuated by its handle 41 to re-lock the head and shell together for a repetition 15 of the threading operation. This combined cam and handle is journaled on the pin 42, Fig. 3, which pin is secured in the rear end wall of the die carrying head 1 and travels freely in the elongated slot 43 20 of the head 4 of the holder.

The mechanism for varying the cut comprises the segment 20 secured to the disk 12, as before mentioned, so that, when the segment is rotated, it will also rotate the disk 25 to locate the position of the locking bolt 15 and thus determine the locked position of the sliding shell 6 with respect to the die carrying head 1. 44 is a handle by means of which the segment is manually operated.

30 When the segment is brought against the stop 45, Figs. 2 and 5, the dies will be in the proper position for taking a roughing cut, and when brought against the stop 46, the sliding shell will be brought closer to the 35 die head and, by this closer relation, the threading dies will be correspondingly advanced to give the finished cut. To prevent accidental shifting of the segment when brought against either of said stops, the 40 pins 47 are located in the sliding shell 6 and their pointed ends engage the depressions 48, Fig. 8, on the underside of the segment. The underlying springs 49, Fig. 5, maintain the engagement of the pins with the segment. These pins have the elongated grooves 45 50 adapted to receive the reduced points of retaining screws to prevent their displace-

ment when the segment is removed. One of said retaining screws, 51, is shown in Fig. 4.

Having thus described my invention, what I claim is:—

1. A die head carrying radially operating threading dies, a holder in which the head has a longitudinal movement, a sliding shell embracing the head and holder, die actuating means carried by the shell to open and close the dies, mechanism for locking the head and shell together carried by the head and shell, tripping mechanism carried by the head and holder whereby the head and shell 55 are unlocked, automatic means for retreating the shell to open the dies, and automatic means for retreating the head.

2. A die head carrying radially operating threading dies, a holder in which the head 65 has a longitudinal movement, a sliding shell overlying the head and holder, die actuating means carried by the shell to open and close the dies, mechanism for locking the head and shell together carried by the head 70 and shell, tripping mechanism carried by the head and holder whereby the head and shell are unlocked, automatic means for retreating the shell to open the dies, and automatic means for retreating the head, and 75 manually operated means for relocking the shell to the head.

3. A die head carrying radially operating threading dies, a longitudinally operating member carrying die actuating members and 80 a rotatable cam member carried by said operating member, a member carried by the die head to engage with the cam member, and a manually operated member for rotating the cam member to vary the distance of 85 the dies from the work and thus effect a roughing and finishing cut.

In testimony whereof I affix my signature in presence of two witnesses.

WILLIAM H. GATES.
